(57) **CLAIM**

We claim the ornamental design for a wearable ultrasound probe, as shown and described.

DESCRIPTION

FIG. 1 is a perspective view of a wearable ultrasound probe;
FIG. 2 is a bottom view thereof;
FIG. 3 is a top view thereof;
FIG. 4 is a right side view thereof;
FIG. 5 is a left side view thereof;
FIG. 6 is a top plan view thereof; and,
FIG. 7 is a bottom plan view thereof.

The broken lines in the drawings depict portions of the wearable ultrasound probe that form no part of the claimed design.

It is certified that error appears in the above-identified patent and that said Letters Patent is hereby corrected as shown below:

On the Title Page

Add before item (57):

“GOVERNMENT SUPPORT ACKNOWLEDGEMENT

This invention was made with government support under contract number W81XWH-17-C-0024 awarded by The United States Army Medical Research and Material Command, and W81XWH-15-C-001 awarded by the Defense Health Program, United States Department of Defense. The government has certain rights in the invention.”

Signed and Sealed this
Sixteenth Day of September, 2025

Coke Morgan Stewart
Acting Director of the United States Patent and Trademark Office
